UNITED STATES PATENT OFFICE

90,703

DESIGN FOR A MOP HEAD

John Glover, Chicago, Ill.

Application October 19, 1931. Serial No. 41,425

Term of patent 14 years

To all whom it may concern:

Be it known that I, JOHN GLOVER, a citizen of the United States, residing at Chicago, Illinois, have invented a new, original, and ornamental Design for Mop Head, of which the following is a specification, reference being had to the accompanying drawing, forming part thereof.

Figure 1 is a perspective view of a mop head

having my new design, the thrums ordinarily employed with the mop head being shown; and

Figure 2 is a perspective view of a mop head showing my design without thrums.

I claim:

The ornamental design for a mop head as shown.

JOHN GLOVER.
